(57) **CLAIM**

The ornamental design of a clear storm panel assembly for protecting a glass window or door, as shown and described.

DESCRIPTION

FIG. 1 is a perspective view of a clear storm panel assembly for protecting a glass window or door showing my new design;

FIG. 2 is a front view thereof;

FIG. 3 is a side view thereof, the opposite side view being a mirror image;

FIG. 4 is a rear view thereof;

FIG. 5 is a top view thereof; and,

FIG. 6 is a bottom view thereof.

The middle portion in FIGS. 1-4 is broken away to disclose indefinite length.
